UNITED STATES PATENT OFFICE.

CLIFFORD E. BAUM, OF SYCAMORE, OHIO.

GUARD AND BRACE FOR FENCES.

Application filed April 3, 1928. Serial No. 267,395.

This invention relates to an improved construction and arrangement of live stock guards utilized in connection with metal fences, and is especially designed for the purpose of preventing live stock such as horses and cattle from riding, jumping and from approaching too close to the fence, or rubbing against it, and thereby damaging or destroying the fencing.

10 The prime object of the invention is to provide simple, strong, economical, durable and effective means for the protection of woven wire fences which will effectually serve to prevent the live stock from jumping the fence, 15 and at the same time prevent the stock from damaging the fencing.

Another object of the invention is to so construct my improved and novel means that it forms an integral part of the fence post, and 20 may be projected a suitable distance beyond one or both sides of the fence to prevent the stock from approaching too close to the fence proper.

The foregoing and such other objects as 25 may appear from the ensuing description are accomplished by the construction, location, combination and arrangement of the several parts hereinafter more fully described, illustrated by the accompanying drawings, and 30 particularly pointed out in the claims appended hereto, it being understood that slight changes in the precise shape, proportions and minor details of the construction may be resorted to without departing from the spirit 35 or sacrificing any of the advantages of the invention.

In the accompanying drawings forming a part of this specification it will be seen that:—

Figure 1 is a perspective view showing the 40 means embodying my invention.

Figure 2 is a side elevation of a portion of the fence post broken away.

Figure 3 is a rear elevation of the device shown in Fig. 2, and

45 Figure 4 is a plan view of the same.

In the embodiment of my invention as illustrated, the guard arms to which the barbed guard wire is secured, which arms constitute one of the essential features of this invention 50 form an integral part of the fence post and are intended to be utilized in connection with a metallic fence including wire fencing, and a specially constructed metal post, such as shown in Figs. 1 and 2 of the drawings, said 55 wire fencing being indicated by the numeral 1, which fencing is supported at intervals by

the post 2 and secured to said posts in any suitable or desirable manner.

The metallic posts as illustrated are formed from a single piece substantially T-shaped in 60 cross-section, having a central portion 3 and a laterally extended portion 4 at each side of the said central portion. Each extended side portion 4 of the post is slotted or cut-away from the central portion from the top down- 65 wardly to a suitable distance dependent upon the location it is preferably desired to attach the barbed guard wire to the post, and each cut-away portion is bent outwardly in opposite directions substantially at a right angle 70 to the post, thus forming an integral arm extending laterally from each side of the post, and in the outer end portion of each of said arms is formed a suitable slot 7 for the reception of the guard wire 6, which is preferably barbed and is supported in the desired spaced relation at either or both sides of the fencing.

It will be seen that the guard arms 4 are 75 strongly braced by means of a strong wire 80 5 which is pressed into the slotted portion of each of said arms and through an opening formed through the central portion of the post, both above and below each of said arms, the ends of said wire being then securely fastened together in any suitable or desirable manner, whereby the said arms are always maintained at a right angle position with relation to fence posts, thus retaining the guard wire in its normal position at all times. 85 90

It will be understood that the arms 4 forming an integral part of each fence post may be formed of any desirable length suitable to retain the barbed guard wire at the desired distance from the fence proper, and that the 95 slotted opening 7 in the outer end portion of each of the said arms is so formed that the guard wire may be easily and readily secured to or removed from the arm.

While I have shown an arm extending from each side of the post, it is evident that only one arm may be extended from the post at one side thereof, when it is desired to use the guard wire at one side of the fence only.

Having thus described my invention what 105 I claim and desire to secure by Letters Patent is:—

1. A fence guard of the character described, comprising a metallic post formed with an extended central portion and a lateral extension at each side of said central portion, laterally extended integral arms 110

formed by cutting away said lateral extension and bending the cut-away portion at a right angle to the post, each of said arms being provided with means for the reception and

5 retention of a barbed guard wire.

2. A fence guard for wire fencing of the character described, comprising a metallic post formed with an extended central portion and a lateral extension at each side of

10 said central portion, each lateral extension being cut away from the top of the post downwardly to a suitable distance and bent at a right angle to the post to form an outwardly extended arm at each side of said post, and

means provided at the outer end portion of each arm for the reception and retention of a barbed guard wire.

3. A fence guard for wire fencing, comprising a metallic post formed with an extended central portion and a laterally extended portion at each side of said central portion, an outwardly extended integral arm formed at a right angle to the post, and a brace wire secured to the outer end of each arm and to the central portion of the post above and below said arms.

CLIFFORD E. BAUM.
